WRENCH

Filed July 2, 1928

Inventor:

Lowell De M. Anderson

UNITED STATES PATENT OFFICE

LON DE MOSS ANDERSON, OF CROSS CUT, TEXAS

WRENCH

Application filed July 2, 1928. Serial No. 289,916.

My invention relates to improvements in wrenches of the end opening, plier type; and the objects of my improvement are, first, to provide a wrench of the said type in which the handles do not pivot at the base of the jaws, but removed therefrom to allow a shank or slender body of stock to support the jaws and having the handles pivot at the remote end of said shank from the jaws.

Second, to provide a better and more convenient means of adjustment of the jaws; third to arrange the handles in such a manner that when they are entirely closed they will have a tendency to remain closed, and when opened past a certain point they will have a tendency to remain open.

With these and other objects in view my invention consists in the novel arrangement described and illustrated in the accompanying drawing, in which:

Fig. 1, is a view illustrating a wrench provided with my improvement; Fig. 2, is a sectional view taken on line 2—2 of Fig. 1; Fig. 3, is a sectional view taken on line 3—3 of Fig. 1.

The numerals 1 and 2 are the handles, the handle 2 extends the entire length of the wrench forming the body of the wrench as at 2^a, and has the jaw 5, also the sleeve 13 formed on its upper end. The sleeve 13 and the jaw 5 can be formed by forming an extended arm on the member 2—2^a as at 13^a, and then bending this arm over to form the sleeve 13 and part of the jaw 5. The part bent over can be firmly attached to the other part of jaw 5 by means of rivets, screws, welding, or any ordinary means of attachment.

The jaw 6 is formed on one end of the curved shank 3, and can be offset slightly to one side so as to lie in the same plane with the jaw 5. The curved shank 3, can be constructed so that the part of the shank adjacent the jaw 6 is of a different curvature to the part adjacent the handle 1.

On the remote end of the curved shank 3 from the jaw 6, extends laterally in one direction the lug or ear 14, and laterally in the opposite direction the arm 7 which may be extended as 7^a and that bent around the

member 2^a to form a sleeve, designated as sleeve 7. The enlarged end of the arm 7—7^a designated as 14^a fits on the opposite side of the end of handle 1 from the lug or ear 14. The hole 16^a receives the opposite end of the pin 4 that passes through the lug or ear 14 and the end of the handle 1.

The end of the handle 1 which is attached to the curved shank 3, by means of the pin or rivet 4, has formed upon it a tooth 12, that engages a toothed rack 10, formed on the edge of the member 2^a. This rack is so curved and positioned relative to the point 11 of guide 13, that when the tooth 12, is engaged at any place along the rack 10 and the handles are in their closed position, the upper point of the jaw 6 will lie in the circumference of a circle whose center is determined by the curvature of the curved shank 3, the curvature of the rack 10, and the position of the rack 10 relative to the point 11 of the sleeve 13. The sleeve 7 is so formed that it can be spaced from the member 2^a at 17 a greater distance than the length of the tooth 12, and is normally held in that position by the spring 9 which is attached to the sleeve 7 at the point 8 by screws, rivets or any ordinary means of fastening.

Now when the part of the sleeve 7 at the point 8 is pressed down against the member 2^a at 17, it will cause the tooth 12 to be pushed out of engagement with the rack 10, then the curved shank 3 with its jaw 6, and carrying the handle 1, can be slid along the member 2^a until the jaws of the wrench are open to the desired width, then when the pressure is released from the point 8 the tooth 12 will again engage the teeth 10, and the movement of the handle 1 will cause the jaw 6 to move toward or away from the jaw 5.

Now it will also be seen that when the handle 1 is turned about the pin 4 as a pivot until it comes to the position of 1^a, that the teeth 12 will disengage from the teeth 10, and the jaws can also be adjusted in this way.

The tooth is set at such an angle relative to the handle 1 and the pin 4, also the spring 9, that when the handle 1 is closed the spring 9 will have a tendency to hold it in a closed position, but when the handles are opened

slightly the tendency of the spring 9, will be to hold the handles in an opened position.

While jaws of this wrench are set at an angle relative to the longitudinal axis of the wrench preferably an angle of between 30 and 60 degrees, the plane of the jaws can also be set at an angle to the plane of the handles and body, preferably an angle of between 10 and 30 degrees, as shown in Fig. 10 2, taken on line 2-2 of Fig. 1.

The invention herein disclosed is a further development of an invention disclosed in my application for Letters Patent on a wrench, filed April 22, 1927, Serial Number 185,817.

15 I am aware that prior to my invention wrenches have been made with one of a pair of operating levers pivoted to the end of the shank of the adjustable jaw and the shank furnished with guides. I therefore do not 20 claim such a combination broadly; but

I claim:

1. A wrench comprising a handle with toothed rack and an end jaw and a sleeved engagement with a movable jaw, a toothed 25 lever pivoted on the movable jaw and engageable with the rack, the sleeved engagement being such as to permit a racked jaw to move into and out of engagement with the toothed lever and means for normally maintaining it in engagement therewith.

2. A wrench comprising a handle with toothed rack and an end jaw and a sleeved engagement with a movable jaw, a toothed lever on the movable jaw and engageable 35 with the rack, a curved shank on the movable jaw, the rack shaped and positioned relative to the sleeve in such a manner as to permit the faces of the jaws to approach each other as radii of a circle, whose center is determined by the curvature of the curved 40 shank and the shape and position of the rack relative to the sleeve.

LON DE MOSS ANDERSON.
